(57) **CLAIM**

The ornamental design for a combined wireless thermometer, as shown and described.

DESCRIPTION

FIG. 1 is an exploded, front, top, and left perspective view of a combined wireless thermometer showing my new design;

FIG. 2 is an exploded, front elevational view thereof;

FIG. 3 is an exploded, rear elevational view thereof;

FIG. 4 is an exploded, left side elevational view thereof;

FIG. 5 is an exploded, right side elevational view thereof;

FIG. 6 is an exploded, top plan view thereof;

FIG. 7 is an exploded, bottom plan view thereof;

FIG. 8 is an exploded, rear, bottom, and right perspective view thereof;

FIG. 9 is an exploded, perspective view shown in a configuration of use;

FIG. 10 is a perspective view shown in a configuration of use thereof; and,

FIG. 11 is a perspective view shown in a configuration of use.

The broken lines shown in the drawings represent portions of the combined wireless thermometer that form no part of the claimed design.

1 Claim, 11 Drawing Sheets
